(57) **CLAIM**

The ornamental design for a display screen or portion thereof with graphical user interface for a manufacturing process status diagnosis display device, as shown and described.

DESCRIPTION

FIG. 1 is a front view of a display screen or portion thereof with graphical user interface for a manufacturing process status diagnosis display device showing our new design; and,

FIG. 2 is a fragmentary enlarged front view defined by lines 2-2 and 2'-2' in FIG. 1.

Broken lines show environmental portions of a display screen or portion thereof, and form no part of the claimed design. The dash-dot-dash broken lines are used to show the boundary between unclaimed and claimed subject matter, and thus form no part of the claimed design.

1 Claim, 2 Drawing Sheets
